(57) **CLAIM**

The ornamental design for an optical receptacle, as shown and described.

DESCRIPTION

FIG. 1 is a front elevational view of an optical receptacle, showing our new design;

FIG. 2 is a rear view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a cross-sectional view taking along line 7—7 of FIG. 1;

FIG. 8 is a cross-sectional view taking along line 8—8 of FIG. 6;

FIG. 9 is a schematic view showing the optical receptacle in used condition, and on a reduced scale;

FIG. 10 is a schematic side elevation view showing the optical receptacle in used condition, on a reduced scale and before insertion;

FIG. 11 is a schematic front elevation view showing the optical receptacle in used condition, on a reduced scale and before insertion;

FIG. 12 is a schematic side elevation view showing the optical receptacle in used condition, on a reduced scale and after insertion; and,

FIG. 13 is a schematic front elevation view showing the optical receptacle in used condition, on a reduced scale and after insertion.

The broken line showing of the environment is for illustrative purposes only and forms no part of the claimed design.
